[57] CLAIM

The ornamental design for a golf shoe sole, as shown and described.

DESCRIPTION

FIG. 1 is a right side elevational view of a golf shoe sole showing my new design;

FIG. 2 is a bottom plan view thereof, the top being conventionally plain;

FIG. 3 is a cross-sectional view thereof as taken from line 3—3 of FIG. 2.

The broken-line showing of a golf shoe in FIG. 1 is environmental only and forms no part of the claimed design.
